SHEAR

Original Filed April 28, 1926

Inventor:
Jesse C. Scoggins

by Hazards and Miller

Attyp. #

UNITED STATES PATENT OFFICE.

JESSE C. SCOGGINS, OF LOS ANGELES, CALIFORNIA.

SHEAR.

Application filed April 28, 1926, Serial No. 105,110. Renewed December 22, 1928.

This invention relates to improvements in shear, and is particularly an improvement over the shear disclosed in my prior Patent No. 1,102,173 issued June 30, 1914.

5 An object of this invention is to provide an improved shear in which there is an adjustable connection between the actuating lever and the movable blade, permitting a considerable movement of the blade and 10 causing the shear to cut with a minimum amount of effort or exertion.

Another object of this invention is to provide a shear on which there is a novel hold-down bar, which can be easily and 15 quickly adjusted to hold an article in position between the blades while it is being cut.

A further object of this invention is to provide an improved shear wherein the hold-down bar can be longitudinally adjusted and 20 be caused to present a guide surface enabling articles to be cut obliquely or at angles at 45 deg. of their length.

A still further object of this invention is to provide an improved shear wherein the 25 frame is quite ruggedly constructed so as to materially lengthen the life or utility of the device.

With the foregoing and other objects in view which will be made manifest in the 30 following detailed description and specifically pointed out in the appended claims, reference is had to the accompanying drawings for an illustrative embodiment of the invention, wherein:

35 Figure 1 is a side elevation of the improved shear, parts being broken away and shown in section,

Fig. 2 is a front view in elevation of the shear, and

40 Fig. 3 is a top plan view of the shear.

Referring to the accompanying drawings wherein similar reference characters designate similar parts throughout, the improved shear consists of a frame which is vertically slotted or bifurcated, providing two spaced forward uprights 10 and two spaced rearward uprights 11. These uprights are connected at their upper ends by means of cross bars 12 and have their lower ends joined to a base 13, which is provided with apertured attaching lugs 14 so that the device can be

rigidly secured to a work bench or the like. On the base 13 there is removably secured a stationary blade 15 which is fastened as by bolts 16. A movable blade 17 carries a removable cutter 18 and is pivoted upon a bolt 19 extending between the forward uprights 10. On the rear end of the movable blade 17 there is pivotally fastened a link 20 which is pivoted as at 21 and which is also pivoted as at 22 to a quadrant shaped member 23, which corresponds to the angular lever provided upon my prior construction.

Between the upper ends of the forward uprights 10 there is pivotally mounted an actuating lever 24 pivoted as at 25, and which has pivotally secured thereto links 26. Between the rearward ends of the links 26 there is disposed a connecting pin 27 which is receivable in any one of the notches 28 formed upon the top of the quadrant shaped member 23. The notches 28 are wider at their bottoms than at their tops, so that the pin 27 will not slip out of any notch regardless of the direction in which the quadrant shaped member 23 is moved. A yoke 29 projects laterally from the side of one of the forward uprights 10, and a hold-down bar 30 extends therethrough. The rear end of 80 the hold-down bar 30 is provided with an arcuate slot 31, through which extends a stud 32 which is slidable therein, and which is provided with a washer 33 and a cotter pin 34. Any other suitable fastening means 85 can be employed, if desired. A wedge 35 rests upon the top of the hold-down bar 30 and has on its rear end depending fingers 36 which embrace the sides of the hold-down bar. The forward movement of the wedge 90 35 is limited by the engagement between the fingers 36 and the yoke 29. While the rearward movement of the wedge when the hold-down bar is in its lowermost position may be limited by the upstanding finger 37, 95 serving also as a handle for the wedge. Forwardly of the yoke 29 the hold-down bar is provided with a bottom flange 38 which extends towards the stationary blade 15. The forward end of the hold-down bar is beveled 100 off at about 45 deg., as indicated at 39. When the hold-down bar 30 is caused to as-

sume its rearmost position permitted by the slot 31, the bevel 39 on the forward end of the hold-down bar is on a line passing through the forward end of the stationary 5 blade 15.

The operation of the shear is as follows: In cutting straight material, the hold-down bar 30 is caused to assume its foremost position, and the material is caused to rest on the stationary blade 15. The hold-down bar 10 is positioned on top of the material and the wedge 35 is forced rearwardly, so that the hold-down bar will hold the material against the blade. The actuating lever 24 is then 15 pulled forwardly, swinging the quadrant shaped member and causing the movable blade 17 to start cutting. In such position the pin 27 frequently occupies one of the notches 28 at the forward end of the quadrant shaped member 23. Because of the link arrangement the lever 24 will be pulled forwardly a considerable distance, while the blade 18 cuts but a short distance. Consequently, the device assumes a position where- 20 in the pivotal connection between the links 26 and the actuating lever will not maintain a maximum mechanical advantage. The pin 27 and the pivotal connection 22 approach the same straight line, so that the mechanical advantage of the machine decreases. 25 Consequently, in order to maintain the maximum mechanical advantage, the pin 27 is lifted out of one of the foremost notches and slipped into one of the rear notches, so that the links 27 will be kept more in a position wherein they are at right angles to the line joining the pin 27 and the pivotal connection 22. When the pin 27 is slipped into the rear notches, the lever 24 is again 30 swung forwardly to complete the cut.

The machine is very advantageously used in cutting articles, especially angle irons on a 45 deg. bevel. In such position the hold-down bar is forced into its rearmost position, 45 and the angle iron is applied as shown in Fig. 3 with the upright web bearing against the forward face 39 of the hold-down bar, and the horizontal web bearing against the under side of the flange 38. The hold-down bar therefore forms a guide for holding the angle iron at 45 deg. to the cutting edges on the blades 15 and 18, and on operating the shear, the angle iron will have one of its webs cut in that manner. It will be noted 55 that the wedge 35 is operable to hold the material against the blade 15 in either of the positions of the hold-down bar.

From the above described construction it will be readily appreciated that the improved shear has several advantages over the construction disclosed in my prior patent in ease of operation and in holding articles to be cut.

It will be understood that various changes 60 may be made in the detail of construction

without departing from the spirit or scope of the invention as defined by the appended claims.

I claim:

1. A shear comprising a frame, a stationary blade thereon, a movable blade positioned upon the frame, a quadrant shaped member pivoted to the frame above the rear end of the movable blade, a link pivotally connected to the rear end of said movable blade and to said quadrant shaped member, an actuating lever pivoted to the forward upper portion of the frame, and a link pivoted to said actuating member, said link carrying a pin receivable in any one of several notches formed upon said quadrant shaped member, the entrances to the notches being narrower than their bottoms. 70

2. A shear comprising a frame, a stationary blade thereon, a movable blade pivoted upon the frame, a quadrant shaped member pivoted to the frame above the rear end of the movable blade, a link pivotally connected to the rear end of said movable blade and to said quadrant shaped member, an actuating lever pivoted to the forward upper portion of the frame, and a link pivoted to said actuating lever, said link carrying a pin receivable in any one of several notches formed upon said quadrant shaped member whereby 80 the mechanical advantage of the shear may always be maintained at a maximum. 90

3. In a shear, a frame, a stationary blade thereon, a movable blade mounted on the frame, means for moving said movable blade relatively to said stationary blade, a yoke mounted upon the side of the frame, a hold-down bar vertically movable in said yoke, and wedge means for holding said hold-down bar against an article placed between said blades. 100

4. In a shear, a frame, a stationary blade thereon, a movable blade mounted on the frame, means for moving said movable blade relatively to said stationary blade, a yoke mounted upon the side of the frame, a hold-down bar pivoted to the frame and extending forwardly through said yoke so as to be vertically movable therein, and a wedge slidable between the top of said hold-down bar and the top of said yoke. 110

5. In a shear, a frame, a stationary blade thereon, a movable blade mounted on the frame, means for moving said movable blade relatively to said stationary blade, a yoke mounted upon the side of the frame, a hold-down bar pivoted to the frame and extending forwardly through said yoke so as to be vertically movable therein, and a wedge slidable between the top of said hold-down bar and the top of said yoke, said wedge having depending fingers embracing the sides of the hold-down bar. 120

6. In a shear, a frame, a stationary blade thereon, a movable blade mounted on the 130

frame, means for moving said movable blade relatively to said stationary blade, a yoke mounted upon the side of the frame, a hold-down bar movable vertically within said yoke and forwardly and backwardly therein, means for holding said hold-down bar in adjusted position, said hold-down bar having its forward end beveled off so that when the

hold-down bar is in its rearmost position, its beveled end will be upon a line extending through the forward end of the stationary blade of the shear. 10

In testimony whereof I have signed my name to this specification.

JESSE C. SCOGGINS.
